E. V. McCARTHY

DEVICE FOR CLEANING FLOOR DRAINS

Filed March 14, 1925

INVENTOR
E. V. McCARTHY
BY *Murphy & Leo.*
ATTORNEYS

UNITED STATES PATENT OFFICE.

EDWARD VINCENT McCARTHY, OF CHICAGO, ILLINOIS.

DEVICE FOR CLEANING FLOOR DRAINS.

Application filed March 14, 1925. Serial No. 15,698.

To all whom it may concern:

Be it known that I, EDWARD VINCENT McCARTHY, a citizen of the United States, and a resident of the city of Chicago, county of Cook, and State of Illinois, have invented a new and useful Improvement in Devices for Cleaning Floor Drains, of which the following is a full, clear, and exact description.

My invention relates to improvements in 10 a device for cleaning floor drains, and it consists in the combinations, constructions, and arrangements herein described and claimed.

An object of my invention is to provide 15 a means of the character described which may be used for loosening accumulations of foreign substances in a floor drain so that the accumulations may be forced down through the drain and through the goose-neck trap usually provided in drain connections.

A further object of my invention is to provide a device of the type described in which particularly novel construction is employed for breaking up and loosening compact deposits of drain trap accumulations such as grease and the like which is usually found in a drain for a garage floor.

A further object of my invention is to provide a device of the type described that is durable in construction, compact in form and thoroughly practical for the purpose intended.

Other objects and advantages will appear 35 in the following specification, and the novel features of the invention will be particularly pointed out in the appended claims.

My invention is illustrated in the accompanying drawings, forming part of this application, in which

Figure 1 is a sectional view of a floor drain showing my improved cleaning device in an operative position.

Figure 2 is an enlarged view along the 45 line 2—2 of Figure 1,

Figure 3 is a sectional view along the line 3—3 of Figure 2,

Figure 4 is a sectional view along the line 4—4 of Figure 2, and

Figure 5 is a sectional view of one of the work engaging members of my invention.

In carrying out my invention I make use of a rigid rod 1 having a handle portion 2 at the upper end thereof and having threads 55 3 at the lower end. The threads 3 provide

means for securing the work engaging part of my cleaning device thereto.

This part consists of a brass disc 4 having an upstanding marginal wall portion 5. The wall 5 extends above the top surface 6 of the disc 4 substantially three-eighths of an inch.

A segmental part of the disc 4 is cut away therefrom leaving only the hub portion 7 thereof at that part. The hub portion 7 has 65 an internal threaded bore 8 which is arranged to receive the threads 3 of the rod member 1.

A portion 9 in the form of a boss is provided on the disc 4 and has its top surface 70 level with the top wall 10 of the marginal wall 5 (see Figure 3). A pair of teeth 11 are formed on the outer wall of the boss 9 and have the points 12 thereof in the plane of the bottom surface 13 of the disc 4. Thus 75 when the teeth 11 are moved into engagement with a substance, that substance is broken up and caused to move upwardly on the inclined front surfaces 13 of the teeth, and hence over the boss 9 upon the surface 80 6 of the disc.

Means for delivering such broken substance from the surface 6 of the disc is provided in a bossed portion 15 at the opposite edge of the disc 4 at that edge opposite to the teeth 11. A sectional view through this portion is shown in Figure 4, from which it will be noted that the inner wall 16 of the bossed portion inclines gradually down to the level of the surface 6 of the disc, while 85 the front wall 14 is cut away at an angle so as to virtually provide an overhanging portion of the disc in the boss 15.

From the foregoing description of the various parts of the device, the operation 95 thereof may be readily understood. My device is primarily intended for use in loosening the compact accumulation of foreign substances such as grease, threads, mud and the like which may be expected to accumulate in the drain pipe of a floor drain just in front of the gooseneck fixture 17 ordinarily employed with such drain pipe. The ordinary type of floor drain is shown in the drawing of Figure 1 at 18. An accumulation 105 of foreign substance is indicated at 19.

The device is inserted in the drain pipe 18, as shown in Figure 1, and the handle 2 turned in a clockwise direction. This causes 110 the teeth 11 to bite into and break up the

adjacent parts of the accumulation 19, which loosened accumulation will be forced up over the surfaces 18 of the teeth and over the boss 9 and upon the surface 6 of the disc.

5. Continued rotation will cause large quantities of the accumulation 19 to be broken up so that with proper flushing it may be forced over the gooseneck portion 17 and down through the drain pipe.

10. When the surface 6 has been entirely covered with such broken and loosened accumulation further rotation thereof will cause it to pass up over the inclined surface 16 of the projection 15 and back beneath the disc. At this time the disc should be withdrawn by movement of the rod 1 and a plunger, such as shown in Figure 5 and indicated at 20, is attached to the rod 1 by means of the thread portion 3. This plunger 20 consists in a metal body portion 21 having internal threads 22 which receive the threaded portion 3 of the rod 1 and a heavy coating of soft rubber applied to the exposed parts of the body 21. This plunger 25 is forced downwardly upon the loosened accumulation 19 with sufficient force to cause the accumulation to move over the gooseneck 17 and down over the drain. At this time sufficient quantities of water 30 should be poured down through the drain 18 to thoroughly flush the drain.

I claim:

1. A device of the character described comprising a work engaging member having the form of a disc with a segmental portion thereof cutaway, teeth formed on said disc and extending into the cutaway portion of the disc, said disc having a marginal wall extending upwardly therefrom, a removable handle member for supporting said disc, said teeth being constructed so as to engage with and force substances upon the upper surface of said disc when said disc is rotated, and an upwardly extending boss on said disc at that portion opposite to the toothed portion, and an inclined surface merging with the top surface of said disc.

disc whereby substances on said disc may be moved up the inclined surface and out of engagement with the disc when the disc is 50 rotated.

2. A device of the character described comprising a work engaging member having the form of a disc with a segmental portion thereof cutaway, teeth formed on said disc and extending into the cutaway portion of the disc, said teeth having substantially flat inclined top surfaces extending from the point thereof upwardly to a plane above the top surface of said disc, said disc having a marginal wall extending upwardly therefrom, a removable handle member for supporting said disc, said teeth being constructed so as to engage with and force substances upon the upper surface of said disc when said disc is rotated, and an upwardly extending boss on said disc at that portion opposite to the toothed portion, and an inclined surface merging with the top surface of said disc whereby substances on said disc 60 may be moved up the inclined surface and out of engagement with the disc when the disc is rotated.

3. A device of the character described comprising a work engaging member having the form of a disc with a segmental portion thereof cutaway, teeth formed on said disc and extending into the cutaway portion of the disc, said disc having a marginal wall extending upwardly therefrom, a removable handle member for supporting said disc, said teeth being constructed so as to engage with and force substances upon the upper surface of said disc when said disc is rotated, the top surface of said teeth being 75 contiguous with the marginal wall, and an upwardly extending boss on said disc at that portion opposite to the toothed portion, and an inclined surface merging with the top surface of said disc whereby substances on said disc 80 may be moved up the inclined surface and out of engagement with the disc when the disc is rotated.

EDWARD VINCENT McCARTHY.
